UNITED STATES PATENT OFFICE

THOMAS S. MERRYLEES, OF YEADON, PENNSYLVANIA

LIQUID COOLER

Application filed September 14, 1928. Serial No. 305,949.

My invention is concerned with the use of solid carbon dioxide or the like as a refrigerant in the cooling of liquids.

Broadly speaking, the aim of my invention is to secure, through provision of facilities in connection with liquid coolers, the advantages inherent to the use of solid carbon dioxide, which, as is well known, is a powerful refrigerant having a temperature in the neighborhood of -100° F., which is available on the market in compact form, conducive to easy handling, and which evaporates entirely without leaving any liquid residue whatsoever.

15 A further object of my invention is to enable conversion to the use of solid carbon dioxide, of standard coolers of the "fountain" type wherein the flow from an inverted storage container is chilled incidental to traverse 20 through a direct communicating refrigerating coil exposed within a receptacle designed for accommodation of a comparatively large quantity of pack ice.

How the above desideratum, as well as 25 other important advantages, can be conveniently attained in practice will be manifest from the detailed description hereinafter when taken in connection with the attached drawings; wherein Fig. I is an axial sectional view, taken as indicated by the arrows I—I in Fig. III, of a fountain water cooler 30 of the coil type converted in accordance with my invention for use of solid carbon dioxide.

35 Fig. II is a sectional view in staggered planes at right angles to that of Fig. I, taken substantially as indicated by the arrows II—II in the latter illustration.

Fig. III is a part plan view of the cooler 40 with one component of the top cover removed, and a part horizontal section taken as indicated by the arrows III—III in Fig. I; and,

45 Fig. IV is a perspective view of a thermal transfer element forming a part of my conversion means.

With reference to these illustrations, the numeral 10 designates comprehensively, the casing of the cooler, the same being of cylindrical configuration and constructed with double side walls of metal with thermo-insula-

tion interposed as at 11. At the top, the receptacle 10 is bridged by a cross bar 12 which affords support for the contiguous edges of semi-circular top cover sections 13, 14. A flat horizontal coil 15 in the bottom of the receptacle 10 communicates with an upward conical reservoir 15^a over which a storage container in the form of a bottle 16, for the liquid to be cooled, is inverted with maintenance of a fluid tight seal of the bottle mouth within said reservoir 15^a, in a well known manner. As shown, the bottle 16 is sustained upright by a flared neck projection 17 upstanding around a receiving opening in the cover section 13, through which the neck of said bottle is introduced into the reservoir 15^a. The liquid is drawn from the cooler 10 under control of a faucet 18 attached to the projecting end of a pipe 19 that extends downward within the receptacle 10 and connects into the terminal end of the coil 15. Ordinarily the space within the cooler receptacle 10 is filled with cracked ice, the water within the coil 15 being cooled through contact of the ice with said coil.

To convert a typical coil cooler such as just described for use of solid carbon dioxide, I first place within the bottom of the receptacle 10 a layer of thermo-insulation 20 which may be a composition of ground cork with a suitable cohering binder, and thereupon place the refrigerating coil 15 so as to rest on said insulation. I next superimpose upon the coil 15 a thermal transfer element 21, preferably of porcelain or like material, capable of communicating the refrigerating effect of solid carbon dioxide modified to preclude freezing. This transfer element 21 has the discous configuration of Fig. IV, with notches 22, 23 to clear the reservoir 15^a and the pipe 19 incidental to introduction into the receptacle 10. From Figs. I and II it will be noted that the area of the element 21 corresponds substantially to that of the refrigerating coil 15, both being somewhat less in diameter than the interior of the receptacle 10 so that no direct circumferential contact is made with the wall of said receptacle. With the discous element 21 in place, I completely fill the receptacle 10 with insulate

material 24, except for provision of an upwardly tapered chamber 25 just large enough say, to accommodate a standard pound block B of solid carbon dioxide measuring approximately two by two by four inches, with the block resting on the exposed portion of the top face of the transfer element 21 as clearly shown in Figs. I and II. The chamber 25 is accessible from the top through a counter 10 tapered opening 26 which is protected by a removable plug 27, also preferably of insulate composition.

In the operation of the cooler, converted as described it will be seen that through inter- 15 position of the transfer element 21, the cooling effect of the block B of solid carbon dioxide is distributed over the area of the refrigerating coil 15 moderated to such an extent as to maintain the liquid in said coil at 20 a palatable drinking temperature above the freezing point. By virtue of the heavy insulation 24 surrounding the chamber 25, the element 21 and the coil 15, losses through radiation are effectively precluded. Under 25 these conditions it is actually demonstrable that a pound of the solid carbon dioxide will last as long as twenty or more pounds of ordinary cracked ice at about the same cost, with avoidance of the sloppiness attending 30 the use of the latter refrigerant.

With the foregoing it will be apparent that by resorting to very simple and inexpensive expedients, I am able to convert standard liquid coolers so that solid carbon dioxide can 35 be efficiently and economically used as a refrigerant in them.

Having thus described my invention, I claim:

1. In a liquid cooler adapted for use of 40 solid carbon dioxide or the like as a refrigerant, a refrigerating coil traversed by the liquid to be cooled, and a thermal transfer element in contact with the coil capable of imparting the cooling effect of the solid carbon dioxide moderated to the extent of precluding freezing of the liquid within the coil.

2. In a liquid cooler adapted for use of 45 solid carbon dioxide or the like as a refrigerant, a refrigerating coil traversed by the liquid to be cooled, a thermal transfer element in contact with the coil capable of imparting the cooling effect of the solid carbon dioxide moderated to the extent of precluding freezing of the liquid within the coil, and 50 a jacket of heavy insulation surrounding the coil and the thermal transfer element except for provision of a chamber large enough to accommodate a unit quantity of the solid carbon dioxide in contact with an exposed 55 portion of the surface of said thermal transfer element.

3. Means to convert liquid coolers, for use 60 in them of solid carbon dioxide or the like as a refrigerant, having a horizontal refriger- 65 ating coil for traverse of the liquid to be

cooled within the bottom of an ice receptacle, comprising a thermal transfer element of porcelain or the like capable of imparting the cooling effect of the solid carbon dioxide moderated to the extent of precluding freezing of the liquid in said coil. 70

4. Means to convert liquid coolers, for use in them of solid carbon dioxide or the like as a refrigerant, having a horizontal refrigerating coil for traverse of the liquid to be cooled within the bottom of an ice receptacle, comprising a discous thermal transfer element having an area equal to that of the coil and resting on the latter in direct contact, said element being formed or porcelain 75 or the like for capacity to impart the cooling effect of the solid carbon dioxide moderated to the extent of precluding freezing of the liquid in the coil. 80

5. Means to convert liquid coolers, for use in them of solid carbon dioxide or the like as a refrigerant, having a horizontal coil for traverse of the liquid to be cooled within the bottom of an ice receptacle, comprising a discous thermal transfer element of porcelain 85 or the like over the coil capable of imparting the cooling effect of the solid carbon dioxide supported thereon moderated to the extent of precluding freezing of the liquid, and insulation filling the ice receptacle around the refrigerating coil and the thermal transfer element except for provision of a chamber 90 large enough to conveniently accommodate a unit block of the solid carbon dioxide in contact with an exposed portion of the surface 95 of said thermal transfer element. 100

6. In a liquid cooler adapted for use of solid carbon dioxide or the like as a refrigerant, a refrigerating coil traversed by the liquid to be cooled, a thermo transfer-element 105 in contact with the coil capable of imparting the cooling effect of the solid carbon dioxide moderated to the extent of precluding freezing of the liquid within the coil, and heavy insulation surrounding the coil and thermo transfer-element except for provision 110 of a chamber to accommodate a block of the solid carbon dioxide in direct contact with a portion of the surface of said thermo transfer-element. 115

7. Conversion means for liquid coolers of the type described comprising, a thermo transfer-element of ceramic material capable of imparting cooling effect from a frigorific binary-compound, in combination with a surrounding enclosure of insulate material providing a chamber to accommodate a unit block of said latter material in contact with an exposed surface of the transfer element. 120

8. Conversion means for liquid coolers of the type described comprising, a thermo transfer-element of ceramic material capable of imparting the cooling effect of a frigorific binary-compound, in combination with a surrounding enclosure of insulate material 125

providing an upwardly tapered chamber just large enough to accommodate a unit block of said latter material in contact with an exposed portion of the surface of the transfer element.

9. Conversion means for liquid coolers of the type described comprising, a thermo transfer-element of ceramic material capable of imparting the cooling effect of a frigorific binary-compound, in combination with a surrounding enclosure of insulate material providing an upwardly tapered chamber having a counter-tapered access opening, said chamber being large enough to accommodate a unit block of the binary-compound in contact with an exposed portion of the surface of the transfer-element, and a removable closure of similar insulate material for the aforesaid opening.

10. As an article of manufacture a solid thermo-transfer element of porcelain for liquid coolers and having radial notches therein for the purpose specified.

11. As an article of manufacture a solid thermo-transfer discous-element of porcelain for liquid coolers and having diametrically opposed notches of unequal proportions for the purposes specified.

In testimony whereof, I have hereunto signed my name at Philadelphia, Pennsylvania, this 10th day of September, 1928.

THOMAS S. MERRYLEES.
